UNITED STATES PATENT OFFICE.

HEINRICH WIDMER, OF UNION HILL, NEW JERSEY.

LET-OFF MOTION FOR LOOMS.

SPECIFICATION forming part of Letters Patent No. 741,602, dated October 13, 1903.

Application filed November 4, 1902. Serial No. 130,075. (No model.)

To all whom it may concern:

Be it known that I, HEINRICH WIDMER, a citizen of the United States, residing at Union Hill, in the county of Hudson and State of New Jersey, have invented new and useful Improvements in Let-Off Motions for Looms, of which the following is a specification.

By means of this invention a take-up and let-off can be secured adapted to insure satisfactory weaving.

This invention has been tested in connection with silk-weaving; but of course the scope of the invention is not to be thereby limited.

The invention resides in certain novel features of construction set forth in the following specification and claims, and illustrated in the annexed drawings, in which—

Figure 1 shows a side elevation of a loom. Fig. 2 shows a rear elevation of Fig. 1 or, in other words, a view looking in the direction from the warp to the cloth-beam.

The loom as known comprises the warp-beam *b*, on which is wound warp-threads *a*, passing over roller *c* and carried through the heddles to be formed into sheds for the passage of the shuttle. The finished fabric or cloth is wound on cloth-beam *i*. A certain tension or brake action on warp-beam *b* is secured by weight *1*, whose cords or ropes *2* clasp or run about opposite end parts of said beam *b*.

The parts thus far described are old and form no part of this invention.

The new parts constituting the invention are the eccentric or crank *e* on shaft or stud *f*, rotated by gear *g*, and driving disk or gear *h*. The crank *e* by link *l* oscillates lever *m'* *m*², fulcrumed at *n*. Arm *m*² connects with two ropes or cords *3*, respectively wound, say, two or three times about a respective end of warp-beam *b* and having at their other ends the weight or cross bar *o*. The weight of bar *o* can be varied by applying one or more removable weights *o'*—say, ordinary scale-weights—or any other removable weight that is ready to hand. As the shed closes or the warp-threads come to a common plane the warp-threads slacken, and at the same time the crank *e* (shown at main shaft *f*) moves lever-arm *m'* downward and arm *m*² rises to slacken the cords or flexible connections *3*

and allow weight *o* to descend. This movement of cords *3* tends to rotate warp-beam *b* backward and take up the slack caused by the warp-threads closing the shed. As the shed reopens the crank *e* moves the lever to swing arm *m*² downward and pull cords *3* to lift weight *o* and aid the forward rotation of warp-beam *b*. Excessive tension of the warp-threads in forming a shed is thus avoided. If the threads are delicate—say, in some cases of silk-weaving—excessive strain should be avoided, as otherwise the warp-threads may be torn.

The arrow in Fig. 1 shows the direction in which the finished cloth travels to cloth-beam *i*.

The word "cord" herein of course means a suitable rope or flexible connection of suitable strength and make.

In speaking of a lever *m'* *m*² it is noted that, as shown, there are really two levers at opposite sides of the loom, one lever application for each cord *3*; but as the levers act in unison or the explanation of one lever applies to the other the above description sets forth the operation of this invention.

In place of weights, as *o* or *o'*, a spring or springs can be applied; but a weight is preferred.

What I claim as new, and desire to secure by Letters Patent, is—

1. The combination with the warp-beam of a loom, of means independent of the warp and actuated by the operation of the loom for rotating said beam backward, when the shed closes, sufficiently to take up the slack in the warp-threads.

2. The combination with the warp-beam of a loom, of means independent of the warp and actuated by the operation of the loom, for rotating said beam backward, when the shed closes, sufficiently to take up the slack in the warp-threads, and for facilitating its forward rotation when the shed opens.

3. A loom having a warp-beam, friction cords or connections made to engage or brake at each end of the beam, a cross-bar made to weight one end of the cords and a lever for actuating the other end of the cords, said weight-bar being adapted to receive or seat removable weights for adjusting the brake action.

4. The combination with the warp-beam of a loom, of means, comprising an operating-shaft, a lever reciprocated by said shaft, a cord attached at one end to said lever and extending around said warp-beam, and a weight attached to the end of said cord, for rotating said beam backward, when the shed closes, sufficiently to take up the slack in the warp-threads, and for facilitating its forward rotation when the shed opens.
5. A loom having a warp-beam, a weighted friction-cord made to engage the warp-beam,

and a lever for actuating the cord and beam back and forth to tighten and slacken the warp, said cord and oscillating lever being ¹⁵ independent of the warp.

In testimony whereof I have hereunto set my hand in the presence of two subscribing witnesses.

HEINRICH WIDMER.
